UNITED STATES PATENT OFFICE.

EDWARD J. CARROLL, OF NEW YORK, N. Y.

CASHIER-PROTECTOR.

1,355,890.

Specification of Letters Patent. Patented Oct. 19, 1920.

Application filed August 30, 1919. Serial No. 320,848.

To all whom it may concern:

Be it known that I, EDWARD J. CARROLL, a citizen of the United States, and a resident of the city of New York, borough of 5 Manhattan, in the county of New York and State of New York, have invented a new and Improved Cashier-Protector, of which the following is a full, clear, and exact description.

10 This invention relates to improvements in cashier protectors, an object of the invention being to provide a shield, which is preferably bullet-proof, and which is normally hid from view, but which will, when permitted, quickly move into position to protect the cashier from a burglar in front of his window or desk.

15 A further object is to provide an improved spring pressed shield, normally held out of sight by means of an improved foot operated catch, and which when the catch is operated will quickly move into position to protect the cashier.

20 A further object is to provide a device of the character stated, which can be manufactured and sold at a reasonably low price, and which will be most effective in use.

25 With these and other objects in view, the invention consists in certain novel features 30 of construction and combinations and arrangements of parts as will be more fully hereinafter described and pointed out in the claim.

In the accompanying drawings:

35 Figure 1 is a view in elevation, partly in section illustrating my improvements.

Fig. 2 is a view in section on the line 2—2 of Fig. 1.

40 Fig. 3 is a view in section on the line 3—3 of Fig. 1.

1 represents a partition, such as usually provided in front of cashiers, and other handlers of money in a bank, or other place of business. 2 is the top of the table or shelf 45 on which the money is usually handled, and 3, 3, are standards, secured to the floor 4, and connected at their upper ends by a rail or brace 5.

The standards 3, 3, are made with longitudinal grooves 6 to receive and guide a shield 7 which is preferably of metal and bullet proof.

55 The shield 7 is movable through a slot 8 in the shelf 2, but is normally flush with the top of the same as shown.

A series of coiled springs 9 are positioned between the floor 4 and brackets 10 on the shield 7 and when permitted force the shield upwardly to a position to protect the cashier. 60

Spring cushioned stops 11 on the uprights 3, 3, limit the upward movement of the shield, and handles 12 on the shield facilitate its downward movement to set position. 65

A foot operated, spring pressed catch 13 holds the shield in its set position and constitutes a pivoted lever, supported on a bracket 14 and, at one end engaging a lug 15 on the shield. 70

A pair of electric contacts 16 are moved together when the catch is operated and these contacts are included in an electric circuit with a signal 17 and source of electricity 18 so that when the catch is operated to release the shield, the danger of the cashier can be known at any point desired. 75

The shield is normally hid from view and a burglar will not suspect the fact that the cashier is so protected. Upon any demand for money accompanied by any threatening attitude on the part of a thief, the cashier can put his foot on the catch 13, release the same and allow the shield to spring up in front of him. At the same time the signal 80 85 will be sounded to bring assistance.

The shield may be made in sections as shown, and of any shape and size desired.

Various slight changes might be made in the general form of the parts described without departing from my invention and hence I do not limit myself to the precise details set forth, but consider myself at liberty to make such slight changes and alterations as fairly fall within the spirit and scope of the 90 appended claim. 95

I claim:

A device of the character described, comprising a pair of parallel vertical standards having grooves therein, a shield having 100 its edges movably mounted in the grooves of the standards, springs for forcing said shield upwardly, a foot operated catch normally holding the shield in its lowered position, cushioned stops supported at the 105 upper ends of the standards and limiting the movement of the shield, and handles on the shield projecting laterally beyond the standards.

EDWARD J. CARROLL.
